UNITED STATES PATENT OFFICE.

GEORGE BYRON McCORMICK, OF MILLERSBURG, OHIO.

SPIKE PULLER.

Application filed December 13, 1921. Serial No. 522,031.

To all whom it may concern:

Be it known that I, GEORGE BYRON McCORMICK, a citizen of the United States, residing at Millersburg, in the county of Holmes and State of Ohio, have invented new and useful Improvements in Spike Pullers, of which the following is a specification.

An object of this invention is to produce 10 a means whereby a railway spike can be drawn in an easy and expeditious manner by a single operator without injury to the spike.

A further object is to produce a means for 15 removing spikes from railway ties that includes a hook member which is received over the head of a rail and a spike engaging member which is pivoted to the hook member, said spike engaging member having 20 a rounded face which is designed to rest on a tie and which serves as a fulcrum, the said member having its outer end headed and designed to be forcibly contacted by a sledge or hammer to rock the same on its 25 fulcrum surface and to draw the spike out of the tie.

A further object is to produce a spike puller in which the parts constituting the same shall be small and comparatively light 30 in weight so that the device can be easily handled when being conveyed from place to place and also wherein the parts are of such construction as to readily engage a rail and the spike to be pulled, and wherein 35 the spike engaging element, in counter-distinction to the push bar construction ordinarily employed in such devices is susceptible to blows from a hammer or sledge in removing the spike.

40 A still further object is to produce a spike puller having means associated therewith which serves to force the claw member of the device into engagement with the spike and which also serves as a protector for 45 preventing a separated head of a spike flying against the operator and thereby avoiding the liability of injury in this respect.

The foregoing, and other objects which 50 will appear as the nature of the invention is better understood, may be accomplished by a construction, combination and operative association of parts, such as is disclosed by the drawings which accompany and which form part of this specification.

55 In the drawings:—

Figure 1 is a view showing the improve-

ment in operative position.

Figure 2 is an approximately central vertical longitudinal sectional view through the improvement, the rail being also in section.

Figure 3 is a plan view looking toward the under face of the claw.

Figure 4 is a perspective view of the jaw carrying member.

Referring now to the drawings in detail, the numeral 1 designates a rail which is supported on a tie 2 and is secured thereto by spikes 3.

My improvement contemplates the employment of a yoke 4, the connecting element for the arms of which being formed with an extension 5 that terminates in a downturned widened flange 6. The outer end of the yoke, including the extension 5 and flange 6 provides a hook that is designed to be arranged over the head of the rail 1, the arms of the yoke 4 being directed at a downward angle from the top and from the extension 5 thereof.

Between the arms 7 of the yoke there is pivoted, as at 8 the claw carrying member of the improvement. This member is of a comparatively short length, comprising a shank or stock portion 9 which preferably has its outer end thickened to form the same with a head 10, the stock terminating at its opposite end in a widened portion or body 11 whose under face is rounded as at 12 and whose upper face is arranged at a downward angle and may be rounded. The upper face is indicated by the numeral 13 and the pointed end provided between the faces 12 and 13 is bifurcated, as at 14, thus providing the claws 15 between which the head of the spike is to be received. The under face of the rounded bottom portion 12 of the body, between the claws is grooved, as at 16, and the upper faces of the claws are concaved or rounded inwardly, as at 17 to 100 the engaging edges thereof. The concaved portion 17 provides a seat for the head of the spike.

Secured to the extension 5 and projected toward the stock 9 there is one end of a flat spring member 18. The portion of this spring member between the arms of the yoke is widened, as at 19, and from thence the spring member is slightly rounded or arched, as at 20. This arched portion serves 110 as a hand hold when the device is to be arranged in operative position and also may

serve as a handle when the device is to be moved from place to place. In addition to this, the arched portion 20 is designed to contact with the inner face of the stock 9 5 to swing the stock on its pivot 8 to bring the claws thereof in spike engaging position. The widened portion 19 of the spring serves as a protector for preventing the heads of spikes which may be severed therefrom during 10 the pulling thereof from flying against the face or person of the operator. The pivot 8 is removable, so that the stock and jaw members of the device may be separated for convenience in handling or storing when 15 not in use.

When the hook-like jaw is arranged on the rail and the claw end of the stock is brought by the spring to engage with the spike the operator grasps a hammer or 20 sledge and swings the same into forcible contact with the head 10 of the stock 9. This causes the stock to rock upon the fulcrum surface provided by the rounded bottom portion of the body 11 thereof, swinging 25 the claw end of the said body upwardly, and thus easily and quickly pulling the spike from the tie. Because of the groove 16 in the under face of the body and because of the pocket provided by the depression 30 17 for the head of the shank, and likewise because the claw portion of the improvement exerts an inward push against the spike at the juncture of the head and shank thereof, the spikes will be withdrawn 35 without injury, except the liability of the severing of the head from the shank, incident to weather conditions, and when withdrawn the shank will be held in a spread position between the claws to permit of the 40 ready removal thereof by the operator. With my improvement, only one operator is employed, who may place himself in the most convenient position for wheeling the hammer or sledge, and as only one blow of 45 the sledge is ordinarily required in the removal of the spike, the construction and advantages of my device will, it is thought, be apparent.

The yoke extension 5 is in the nature of a 50 tongue, and the jaw element 6 of the hook is preferably slidable on the tongue, as illustrated in Figures 1 and 2 of the drawings. Between the yoke and the sides of the tongue 5 there are helical springs 21 secured to both the yoke and the inner face 55 of the jaw 6. By this arrangement the jaw is normally forced on the tongue toward the body of the yoke, and also by this arrangement the device will readily adapt itself to

varying thickness of rails. Preferably, and as illustrated by the dotted lines in Figure 1 of the drawings, there is a binding element, such as a thumb bolt 22 screwed in an opening in the top of the jaw 6 to frictionally contact with the tongue 5, and thereby hold the jaw adjusted with respect to the yoke 4.

Having described the invention, I claim:—

1. In a spike puller, a fork member having a hook at one end thereof, a stock having a rounded body pivoted between the arms of the yoke and said body having its pointed edge bifurcated to provide claws, and spring means between the hook and stock exerting a pressure on the stock to 75 swing the same and the body thereof in one direction.

2. In a spike puller, a forked member having a hooked extension, a stock of a comparatively short length having one end 80 formed with a rounded edge which is pivotally secured between the arms of the yoke and which has its outer end terminating in a joint, said joint being bifurcated to provide spike engaging claws, the under face 85 of the head in a line with the bifurcation being grooved and the upper face of the head in a line with the claws being concaved, and a flat spring member secured to the hook having a widened portion arranged 90 between the arms of the yoke and an arched extension which is in contacting engagement with the inner face of the stock.

3. In a spike puller, a yoke including a tongue having downwardly extending arms 95 at one end thereof, a jaw slidable on the tongue, means adjustably securing the jaw on the tongue, a stock having a rounded lower portion which is pivoted between the arms of the yoke, and said lower portion 100 having a pointed end which is bifurcated to provide claws.

4. In a spike puller, a tongue having a yoked end which extends downwardly therefrom, a jaw slidable on the tongue, spring means influencing the jaw in the direction of the yoke, binding means between the yoke and tongue, a stock having a lower rounded portion which terminates in a pointed end and which rounded portion is pivotally secured between the arms of the yoke, the pointed end of the stock being bifurcated to provide claws, and a flat spring member in line with the tongue and disposed between the arms of the yoke.

In testimony whereof I affix my signature.

GEORGE BYRON McCORMICK.
